UNITED STATES PATENT OFFICE.

ALBERT P. MASSEY, OF WATERTOWN, NEW YORK, ASSIGNOR TO THE EAMES VACUUM BRAKE COMPANY, OF SAME PLACE.

AUTOMATIC VALVE FOR REGULATING FLUID-PRESSURE.

SPECIFICATION forming part of Letters Patent No. 358,866, dated March 9, 1887.

Application filed October 16, 1886. Serial No. 916,396. (No model.)

To all whom it may concern:

Be it known that I, ALBERT P. MASSEY, a citizen of the United States, residing at the city of Watertown, in the county of Jefferson 5 and State of New York, have invented certain new and useful Improvements in an Automatic Valve for Regulating Fluid-Pressure, of which the following, taken in connection with the accompanying drawing, is a specification.

10 My invention relates especially to operating air-brakes; but it will prove useful in many cases where a fluid-pressure is to be varied at the will of the operator—as, for instance, to apply the grip on cable-cars or for pneumatic 15 elevators.

It consists of an arrangement of valves adjusted to movable valve-seats in such manner that the valve is opened by moving the valve-seat away from the valve, while the valve is 20 closed automatically when the desired pressure is reached.

It may be used for actuating pistons or diaphragms, whether the fluid-pressure is in excess or below the atmospheric pressure. The 25 apparatus shown is arranged for the vacuum system of car-brakes.

The drawing shows a sectional view of the apparatus in its normal position when a train is running.

30 The inside of the valve-case A' is connected directly with the reservoir or source of vacuum by pipe A'. The intermediate valve-chamber, S, is connected with the brake diaphragms or cylinders through valve V and pipe V'. The chamber S is connected with the chamber D by passage T. The chamber Z is open to the atmosphere.

B and C are elastic diaphragms which separate the chambers D, A', and Z from each 40 other.

F is a valve controlling an opening between valve-case A and the intermediate valve-case, S.

M is a movable seat for valve F, and works 45 as an air-tight piston through the case A.

O is a valve controlling an opening between valve-case S and the atmosphere through a gauze strainer, W'.

R is an air-tight piston working through 50 case W, and forms a seat for the internal valve, O.

N is a walking-beam secured to shaft Y and connected by pins to the lugs R' of piston R and to the lugs M' of piston M.

X is a handle outside the case attached to the 55 shaft Y for actuating the walking-beam N.

H is a bell-crank revolving about fixed fulcrum J. It is connected to diaphragm B by link K, and to diaphragm C by link L in such a manner that when H revolves about fulcrum J the effective leverage of one diaphragm to turn the bell-crank increases, while the effective leverage of the other diaphragm decreases. There is a flat surface on H at H', on which the stem of valve F rests at certain times. 65 There is also connected with H by H' a spindle, P, which passes through the case A and supports the valve O at certain times.

V is a check-valve, that prevents leakage when the brake-pipe is opened at any other 70 point.

G and G' are wires connected with battery G' and with electro-magnets on the cars.

The operation is as follows: When the train is running, a vacuum is maintained in the case 75 A through the pipe A', which may be connected with the reservoir, pump, or ejector. The valves are all closed. To apply the brakes slightly, the handle X is moved in the direction of the arrow a little way. This revolves 80 the walking-beam N in the same direction, and by means of the lugs R' and M' raises the annular piston R and depresses the annular piston M. Raising the piston R has no effect upon the inclosed valve O, which remains 85 seated, but depressing the piston M carries the valve-seat away from the valve F, which now rests upon bell-crank H. This opens the valve F and allows air to pass from the chamber S to the chamber A', connected with the vacuum-reservoir. As the check-valve V is connected 90 with the walking-beam N, it would be open when the handle was moved as described. Therefore there would be free communication between the brake-diaphragms and the chamber A', connected with the vacuum-reservoir. 95

Consequently the brakes would begin to apply. Before the valve F was opened there was the ordinary atmospheric pressure in the chamber S and also the chamber D, which is connected 100 with chamber S by the passage T. There was also atmospheric pressure in chamber Z.

through the opening Z' . As the area of diaphragm B is greater than the area of diaphragm C, the excess of atmospheric pressure in B kept the bell-crank H in contact with the stem of valve F. As soon as the valve F was open a vacuum began to form in chamber S, and consequently in chamber D, through passage T. This would reduce the atmospheric pressure on diaphragm B until the pressure on diaphragm C was able to overbalance it. This would begin to revolve bell-crank H away from valve-stem F, and thus allow the valve F to close by gravity. The distance to which the bell-crank H would revolve is determined by the difference in pressure on the two diaphragms B and C. Consequently, if the handle were moved but a little, the piston M would move away from the valve F but a little, and a slight vacuum in the chambers S and D would cause the bell-crank H to revolve sufficiently to allow the valve F to close. If the handle were moved farther, another point would be reached at which the bell-crank would revolve away from F and allow it to close. Thus it may be seen that by moving the handle to the proper position any degree of vacuum may be obtained in the chamber S and its connected brake-diaphragms, while the valve F would be automatically closed when the desired vacuum was reached.

The valve O and its piston R are for the purpose of releasing the vacuum in chamber S and the brake-diaphragms to any desired amount. When the handle was turned toward the arrow, the valve O remained seated; but as the bell-crank H revolved it kept the spindle P in close proximity to the valve-stem O. If the handle be moved in the opposite direction from the arrow it would depress the annular piston R, but the valve O would rest upon the spindle P and open the valve O to the atmosphere. This would reduce the vacuum in chamber S and the brake-diaphragm, but it would also reduce the vacuum in chamber D. When the pressure was increased sufficiently in chamber D to overbalance the constant pressure in Z, the bell-crank would revolve until the spindle P was drawn away from valve O, which would then seat itself by gravity and prevent further admission of air. Thus it may be seen that the operator could release the vacuum from chamber S to any desired amount, and the valve O would automatically close itself when that point was reached.

If this device were placed between a reservoir and a train-pipe to which a series of automatic valves were attached for working brakes, the pressure in the train-pipe could be varied at will or maintained at any desired point.

When this device is used for one system of car-brakes in which the automatic brake-valves

are actuated by air-pressure and also by electro-magnets, the wires G and G' are introduced. These wires are electrically connected with electro-magnets throughout the train and with battery G², so that when in contact in chamber S there will be an electric current through the electro-magnet. Thus the same motion of the handle that opened the valve O will cause an electric current to pass through the electro-magnets, while the automatic separation of spindle P from the valve O will break the circuit from the electro-magnets.

It is obvious that by a suitable arrangement of valves this device would operate just as well where the reservoir-pressure was in excess of the atmospheric pressure, and I therefore claim such use in these specifications. It is also obvious that a spring might be used in place of the diaphragm C to produce the pressure caused by the atmosphere on C.

There are many mechanical arrangements by which the movable valve-seats M and R may be actuated, which will suggest themselves to any one skilled in mechanics.

The diaphragms B and C, in combination with bell-crank H, revolving about fixed fulcrum J, and actuating a valve, as at F, I have made subject to a claim in an application filed October 22, 1886, Serial No. 216,926.

What I claim as my invention, and desire to secure by Letters Patent, is—

1. In a device for regulating the flow of fluid-pressure, a valve seated upon an adjustable seat and governed by a stop, which is automatically removed by a change in the ratio of the pressures in the two chambers on opposite sides of said valve.

2. In a fluid-pressure brake, the diaphragms B and C, suitably connected with bell-crank H, revolving about a fixed fulcrum, J, in combination with valve F and adjustable seat M.

3. In a fluid-pressure brake, the valves O and S, with their adjustable seats R and M so arranged as to be operated by a single handle.

4. In a fluid-pressure brake in which electricity is used to actuate the valves, a circuit-breaker one pole of which is attached to the air-valve and the other pole is attached to an automatic mechanism for holding such valve open in such a manner that the circuit will be broken when the automatic mechanism moves away from contact with the valve, or the valve is moved away from the automatic mechanism.

In testimony whereof I have signed my name to this specification, in the presence of two subscribing witnesses, on this 14th day of October, A. D. 1886.

ALBERT P. MASSEY.
